US00D556165S

(12) **United States Design Patent** (10) **Patent No.:** **US D556,165 S**
(45) **Date of Patent:** **** Nov. 27, 2007**

(54) **MOBILE PHONE**

(75) Inventors: **Young-Sae Kim**, Los Altos, CA (US);
Chi-Young Ahn, Seoul (KR);
Young-Ju Yeo, Seoul (KR);
Chang-Hwan Hwang, Goyang-si (KR)

(73) Assignee: **Samsung Electronics Co., Ltd.**,
Suwon-Si (KR)

(**) Term: **14 Years**

(21) Appl. No.: **29/243,534**

(22) Filed: **Nov. 28, 2005**

(30) **Foreign Application Priority Data**

Jun. 13, 2005 (KR) 30-2005-0019717

(51) **LOC (8) Cl.** **14-03**

(52) **U.S. Cl.** **D14/138**
